To all whom it may concern:

Be it known that I, JAMES A. - 5 The features of the design are the form, shape, and arrangement of the parts forming

or constituting the hook-pin, and which may be mentioned as follows: the back or base 1, the upwardly-turned hook 2, the downwardly-turned hook or keeper 3, and the pin 4. 20

Having described my invention, what I claim as new, and desire to secure by Letters Patent, is—
